UNITED STATES PATENT OFFICE.

WINFRED ROWLAND THOMAS HILL, OF ASHEVILLE, NORTH CAROLINA, ASSIGNOR OF ONE-
THIRD TO J. M. HORNER, OF ASHEVILLE, NORTH CAROLINA.

PIANOFORTE.

No. 901,615.

Specification of Letters Patent.

Patented Oct. 20, 1908.

Application filed October 4, 1907. Serial No. 395,902.

To all whom it may concern:

Be it known that I, WINFRED R. T. HILL, a subject of the King of Great Britain, residing at Asheville, in the county of Buncombe 5 and State of North Carolina, United States of America, have invented a new and useful Improvement in Pianofortes, of which the following is a specification.

My invention is an improvement in piano 10 fortés and consists in certain novel constructions and combinations of parts hereinafter described and claimed.

Referring to the drawings forming a part hereof—Figure 1 is a cross section of a piano 15 frame showing the improved construction, the section being taken through that part of the frame having three strings for each note. Fig. 2 is a detail in section through the top of the frame in the part having two strings for 20 each note. Fig. 3 is a similar view through the bass having only one string for each note. Fig. 4 is a detail in perspective of one of the brackets to which the strings are connected.

Referring to the drawings, the main frame 25 1 is of ordinary construction, and on opposite sides of this frame are arranged the sound boards 2 and 2^a, also of usual construction. The sound boards are supported at their edges by strips 4 and 4^a glued to the 30 main frame, and bridges 3 and 3^a are glued upon the top of the sound boards and may be formed with a continuous curve to conform to the length of the vibrating strings. The strips 4 and 4^a are set slightly to the outer 35 side of the bridges 3 and 3^a, so that the sound boards rest on the strips 4 and 4^a, and about one half of the bridges lie directly over the said strips. This prevents sagging of the sound boards from the pressure of the strings 40 on the bridges. As shown the sides are alike, and the bridges placed exactly opposite on both sides, so that the pressure on opposite sides is balanced and sidewise bending of the main frame is prevented.

The strings S and S' are fastened at the 45 bottom to the opposite edges of a metal plate 10, which extends across the bottom of the main frame, and the strings rest on the bridges 3 and 3^a at top and bottom. The 50 strings are fastened at the top to pins 21, on angular brackets 20, there being one bracket for each string. The brackets rest on the ledges of angle plates or strips 12 and 12^a,

seated in rabbets in the top edge of the main frame, and said brackets are engaged and held by nuts 19, which screw on the opposite ends of threaded tuning pins 13, 14 and 15, which pins extend through the opposite plates 12 and 12^a and the top of the main frame.

In that section of the instrument having three strings, the plates 12 and 12^a have three steps; in that section having two strings the plates have two steps, and in the bass they have one step, as shown in Figs. 1, 2 and 3, respectively. In the form shown in Fig. 1, spacing blocks 11 and 11^a are glued to the frame to give the space requisite for placing the three plates. It is obvious that when the nuts 19 are turned, the brackets 20 will be moved toward or from each other to tighten or loosen the strings.

Fig. 1 shows part of an action for sounding both sets from one key-board, and 6 and 6^a are rails running across the front and back, 75 the said rails carrying the squares 7 and 7^a, and the front rail may be operated by an ordinary foot pedal. When the rail is lowered, the end of the square rests upon the end of the key 8, and since the square 7 is 80 connected by the wire 22 with the square 7^a the movement of the key 8 will operate both squares at the same time. The abstract 9 operates the front action, not shown. An abstract 9^a is operated by the free end of the 85 square 7^a, the abstract 9^a operating the rear action. It will be evident that when the rail 6 is lowered so that the end of the square 7 rests on the end of the key, both the front and rear action will be operated by the key, 90 while, when the rail is raised to bring the square out of contact with the key, only the front action will be operated.

It will be observed, that the tension on the opposite sides of the frame is balanced, so 95 that bending strain on the frame is eliminated, also that the sound boards are made without ribs, the strings resting on a bridge at each end.

The double set of strings permits wide 100 range of volume of sound as well as the use of two key-boards, one at the front and one at the back if desired, or two key-boards in front, one using the front set of strings and one the back; or the strings of both front 105 and back can be used for the treble, the bass

using the front only, thereby giving better balance of sound and avoiding any deficiency in the treble.

I claim:

- 5 1. In a piano forte, the combination of a main frame, a sound board on the side of the same, strips between the edges of the sound board and the frame, strings in tension over the sound board, and bridges between the strings and the sound board, said bridges and strips being located opposite each other.
- 10 2. In a piano forte, the combination of a

main frame, strings in tension on both sides thereof, screws extending through the edge of the frame and having nuts upon both ends thereof, and connections between the nuts and the corresponding strings on opposite sides.

WINFRED ROWLAND THOMAS HILL.
